United States Patent Office

Des. 223,733

Patented May 30, 1972

223,733

CIGARETTE MERCHANTISER

Robert B. Nielsen, Park Ridge, Ill., assignor to Frank Mayer & Associates, Inc., Grafton, Wis.

Filed Dec. 7, 1970, Ser. No. 26,342

Term of patent 14 years

Int. Cl. D6—06

U.S. Cl. D80—9

Fig. 1

Fig. 2

Fig. 3

Fig. 4

Fig. 5

Fig. 6

FIG. 1 is a perspective view of a cigarette merchandiser showing my new design;

FIG. 2 is a front elevational view thereof;

FIG. 3 is an elevational view taken from one side thereof, the opposite side being a mirror image of the side shown;

FIG. 4 is a rear elevational view thereof;

FIG. 5 is a top plan view thereof; and

FIG. 6 is a bottom plan view thereof.

I claim:

The ornamental design for a cigarette merchandiser, as shown and described.
